US00D415400S

United States Patent

[19]

Mizutani et al.

[11] Patent Number: Des. 415,400

[45] Date of Patent: ** Oct. 19, 1999

[54] POWER SHEARS

8138981 1/1993 Japan .

[75] Inventors: **Makoto Mizutani; Norifumi Niwa; Tadayoshi Tsuchiya**, all of Anjo, Japan*Primary Examiner*—Nelson C. Holtje
Attorney, Agent, or Firm—Dennison, Meserole, Scheiner & Schultz[73] Assignee: **Makita Corporation**, Anjo, Japan

[57] CLAIM

[**] Term: **14 Years**

The ornamental design for power shears, as shown and described.

[21] Appl. No.: **29/098,328**

DESCRIPTION

[22] Filed: **Dec. 24, 1998**

FIG. 1 is a perspective view of power shears showing our new design;

[30] Foreign Application Priority Data

Jun. 26, 1998 [JP] Japan 10-18525
Jul. 8, 1998 [JP] Japan 10-19873

FIG. 2 is a front elevation view thereof;

[51] LOC (6) Cl. **08-05**

FIG. 3 is a rear elevation view thereof;

[52] U.S. Cl. **D8/69; D8/61**

FIG. 4 is a left side elevation view thereof;

[58] Field of Search D8/61, 69, 70;
30/228, 206

FIG. 5 is a right side elevation view thereof;

[56] References Cited

FIG. 6 is a top plan view thereof;

U.S. PATENT DOCUMENTS

FIG. 7 is a bottom plan view thereof;

- D. 209,442 11/1967 Greene .
D. 216,612 2/1970 Zuro D8/61
D. 295,516 5/1988 Clophus et al. D14/133
